UNITED STATES PATENT OFFICE.

EMIL R. LOCHMAN, OF MILWAUKEE, WISCONSIN.

MACHINE FOR CORRUGATING MATERIAL.

1,263,577.

Specification of Letters Patent. Patented Apr. 23, 1918.

Application filed July 17, 1915. Serial No. 40,356.

To all whom it may concern:

Be it known that I, EMIL R. LOCHMAN, a citizen of the United States, and resident of Milwaukee, in the county of Milwaukee and State of Wisconsin, have invented new and useful Improvements in Machines for Corrugating Material, of which the following is a description, reference being had to the accompanying drawings, which are a part 10 of this specification.

The invention relates to corrugating machines.

The invention is designed more particularly to provide a machine for corrugating brittle material such as wood veneer though it may be used with equally beneficial results in corrugating straw board or other pressible sheet material.

The invention is further designed to provide a machine for producing interlockable corrugated material, that is, material in which each corrugation is interlockable with any other corrugation of the material. Plain corrugated material is well known 25 and used for packing articles for shipment but the interlockable corrugated material is superior to the plain material because the corrugations permit the material to be wrapped around an article 30 and to be fastened by its own corrugations thus dispensing with any additional fastening means and further because it produces by its own formation a stronger material due to the inward bent form, making 35 of each corrugation a complete self-supporting arch, resisting a great deal of pressure while the ordinary corrugation would give away by spreading out flat.

The invention consists in the several features hereinafter set forth and more particularly defined by claims at the conclusion hereof.

In the drawings:

Figure 1 is a vertical sectional view of the 45 machine embodying the invention, said section being taken along the line 1—1 indicated in Fig. 2;

Fig. 2 is another sectional view of the machine, said section being taken along the line 2—2 of Fig. 1, the aprons being removed;

Fig. 3 is a detail view of one of the apron supports;

Fig. 4 is a section taken on the line 4—4 of Fig. 2;

Fig. 5 is a detail view of the front end 55 of the machine showing the sheet material introduced between the corrugation forming aprons;

Fig. 6 is an enlarged detail view of the 60 rear of the machine;

Fig. 7 is a detail view of the machine showing the manner of driving the aprons;

Fig. 8 is a view of one of the corrugating bars forming the apron, part being broken 65 away;

Fig. 9 is another view of one of the corrugating bars showing its rod and link connection and Figs. 8 and 9 together show oppositely disposed corrugating bars;

Fig. 10 is a section taken on the line 10—10 of Fig. 9;

Fig. 11 is a section taken on the line 11—11 of Fig. 9;

Fig. 12 is a section taken on the line 12—12 75 of Fig. 9;

Fig. 13 is a detail view of a modified form of drive for the upper apron; and

Fig. 14 is a detail view of one of the stripper blocks.

Before proceeding with a detailed explanation of the machine, the method of producing the corrugated material will be described. This consists in preferably moistening the sheet material and then introducing the material in this condition between intermeshing corrugation-forming endless aprons to press the material between them, heating the material, if previously moistened, while it is being pressed into shape 85 by the aprons to dry and set it and then stripping the material from the aprons. In making corrugated material from wood veneer it is practically necessary to moisten the material before forming the corruga- 90 tions.

The machine for carrying this method into effect consists of a pair of oppositely disposed intermeshing corrugation-forming flexible endless aprons A and B, means for supporting said aprons, means for spreading the corrugation-forming means of the aprons, means for feeding material to the machine, means for driving said aprons, and means for removing the corrugated material from the 105 aprons. In case the material is moistened

previous to its introduction into the machine means are provided for drying the material while on the aprons.

Each apron consists of a plurality of transversely extending corrugation-forming bars 15 and means for joining said bars together to form a flexible endless conveyer and former.

Each bar 15 is preferably substantially rectangular-shaped in cross section and its upper portion is provided with transversely extending arc-shaped grooves 17 adjacent its upper edge, the bar extending upwardly from the neck 18 formed by the grooves to form a transversely extending rounded head 19. In the present instance I have shown bars for making interlockable corrugated material in which the neck 18 is smaller than the head 19. The bars 15 are disposed side by side so that adjacent grooves 17 form grooves 20 in one apron which are adapted to receive the heads 19 on the bars of the oppositely disposed apron so that said aprons will intermesh with each other.

The means for joining the bars 15 together to form a flexible apron comprises a plurality of round rods 21 and means for pivotally and flexibly securing the rods to adjacent bars of the apron. This means comprises semi-circular grooves 22 formed in both sides of the bars preferably below the longitudinal axis of the bar and each rod 21 is adapted to be disposed between the grooves 22 in two abutting bars and means are also provided for pivotally connecting the rods together consisting of links 23, 24, and 25, each link connecting together and in succession two adjacent rods forming a chain so that three bars and three links will be secured together as shown in Fig. 10 and this connection is again repeated to form the complete apron which may consist of as many corrugating bars or links as may be desired. The bars 15 are provided with notches adjacent their bottom edge for receiving the connecting links 23, 24 and 25. The sides 22' adjacent the bottom edge of the bar and the grooves 22 are slightly tapered inwardly to permit of a flexible movement of the bars with respect to each other and a pivotal movement upon rods 21. It will be noted that the form of pivotal connection between the rods 21 and the bars 15 will cause a pressure exerted upon any one of the bars to be transmitted to and therefore resisted by the adjacent bars.

The means for supporting the aprons A and B comprises a frame 27, transversely extending bridges 28 mounted in the frame, supporting means for the apron carried by said bridges and longitudinally extending plates 28' secured to the bridges and disposed between them.

The bridges 28 each consist of trans-

versely extending portions 29 secured to the frame, and outwardly extending web or bearing portions 30 integral with said portions 29. Adjacent the portions 29, the webs 30 of the bridge are provided with recesses 31 and semi-circular recesses 32 and bearing plates 33 having semi-circular recesses 34 registering with the recesses 32 are adapted to fit in the recesses 31. The ends 35 of the webs 30 of three of the bridges are provided with bearing recesses 36, and bearing plates 37 provided with bearing recesses 38 registering with the recesses 36 are secured to said ends. The end of the upper right hand bridge is provided with recesses 31 and bearing recesses 32 and bearing plates 33 having bearing recesses 34 registering with the recesses 32 are adapted to fit in the recesses 31, Figs. 1, 2 and 4.

The supporting means for the aprons includes rollers 39 provided with reduced end 40 and reduced portions 41 which reduced end and portions are adapted to revolvably fit within the bearings formed by the recesses 32 in the web and the recesses 34 in the bearing plates 33. The supporting means for the apron also includes shafts 42 which are revolvably mounted in the recesses 36 and 38 and these shafts carry apron supporting rollers 43. The bottom edge of the apron bars 15 ride upon the rollers 39 and 43 as shown in Fig. 1.

The means for spreading the corrugating bars so that their upper ends will open to receive and to permit the discharge of the material consists of the rollers 39 above described, the connection of the bars with the rods above described and the tapered ends of the bars. To accomplish the spreading of the bars as shown in Figs. 5 and 6 the diameter of the rollers 39 must be such as to permit the spreading of the bars of predetermined thickness that is the rollers 39 must cause the apron bars to travel over a certain predetermined arc so that the bottom edges of the bars contacting with the rollers will be drawn together to bring the tapered sides 22' of the bars into abutting contact with each other thus moving the bottom ends of the bars inwardly toward each other and the corrugation-forming portions of the bars outwardly. This spreading of the corrugation-forming portions of the bars is absolutely necessary when the bars are provided with interlockable corrugation-forming portions for the material must be introduced between the bars of the oppositely disposed aprons before said aprons are brought into interlocking intermeshing relation with each other. When the corrugating aprons are led over a plane surface, the tapered sides of the bars of two adjoining bars spread a certain distance while the sides of the bars above the

point of pivotal connection with rods close up tightly and in that condition form a solid bed. However, when these corrugating aprons are led over the rollers 39, then 5 the corrugation-forming ends of the bars spread a certain distance while the tapered sides close tightly against one another to form a solidly locked member like a section 10 of a solid corrugating roller, with the outer parts spread so that the heads 19 of the 15 apron A may fold into the necks 18 of the apron B and vice versa. The edges of the corrugating bars of the apron A are tapered more than those of the apron B to make the 20 apron A more flexible so that the corrugating bars of the two aprons can more readily mesh and fold into each other without cutting or injuring the material while it is being fed in between these aprons to be corrugated. The apron B will be designated as the tight apron, while the apron A will be known as the loose or follower apron.

The means for driving the aprons comprises means for driving the lower apron 25 and consequently the upper apron as the upper apron will move with the lower apron since the corrugating bars on the aprons intermesh with each other. This means consists of sprockets 44 mounted on the 30 shafts 42, said sprockets intermeshing with the round rods 21 of the apron and the bars 15 having notches 45 therein to accommodate the sprockets, Figs. 7, 8 and 9. In Fig. 13 I have shown a modified 35 form of driving means which consists in extending the bottom edges of the bars and shaping them to form teeth 46 which mesh with the teeth on the sprocket 44'. This construction shown in Fig. 13 may be used 40 if desired in connection with either one of the aprons. The shaft 42 at the front of the machine is provided with a pulley 47 which is adapted to be connected up to a suitable source of power by a belt connection. The rotation of the front shaft 42 45 will move the lower apron, the upper apron and the rollers supporting these aprons.

A table 48 is mounted on the frame at the front of the machine having its upper surface in line with the center line between the aprons and a roller 49, preferably driven 50 at a slower speed than the material is taken by the aprons, mounted on the frame of the machine co-operates with said table to introduce or feed the sheet material C under a certain tension into the bight of the corrugation-forming means.

The means for removing the corrugated material from the apron consists of bars 55 and 51 carrying stripper blades 52 and 53 respectively adapted to register in slots 54 and 55 in the bars of the upper and lower apron respectively to contact with the bottom surface of the material, Figs. 1,

6, 8, 9 and 12. The blades 53 at the rear 65 of the machine engaging in the slots 55 remove the corrugated material from the apron B and the blades 52 at the front of the machine engage in the slots 54 and remove the material from the apron A so that 70 it passes onto a delivery table 56, Fig. 1. The bar 51 is provided with a guard and guide member 57 to prevent the material from leaving the upper apron B while the bars of said apron are partly extended, passing 75 around the roller 43.

The means for drying the material while on the aprons comprises burners 58 mounted beneath the aprons where said aprons contact with each other and burners 59 mounted 80 beneath the upper run of the apron A. As the material is moistened it is necessary to provide some means for allowing the moisture to escape from between the plates during the drying operation and this consists 85 of a plurality of vertically extending slots 60 in the bars 15, Figs. 8, 9, 11 and 12. A plate 61 is mounted above the lower run of the apron A upon the bridges 28 to divide the machine into upper and lower chambers 90 and deflect the moisture from the upper chamber.

The operation of the machine is as follows: The material C is delivered in a moist condition upon the table 48 and led between 95 said table and the feed roller 49 to a position between the aprons A and B adjacent the rollers 39 at the front of the machine. The bars of the aprons being spread at this point the material is fed between the bars and as 100 it passes along between the aprons A and B and said rollers, the bars close up into interlocking relation forcing the material to form to the interlocking configuration of the bars and pressing it and feeding it 105 along as the aprons pass over the lower plate 28'. During its passage over said plate the heat from the burners 58 partially dry the material so as to set it and when it has traveled to the rear of the machine the 110 stripper blades 53 remove it from the lower apron B at the point where the aprons diverge and the corrugating bars are again spread apart by the cooperation of the rollers 39 and the tapered ends of the bars. 115 On leaving the lower apron, the material is carried along by the upper apron and over the upper plate 28' where it is subjected to the heat from the burners 59 to further dry and set it. Thus the material is first dried 120 while in the intermeshing run of the upper and lower aprons and then after being stripped from the lower apron it is still held firmly by the upper apron and dried during its upper run and more readily dried in this 125 upper run because one side of the material is exposed while held by the bars thus giving the moisture a better chance to escape

than when the material is gripped between the intermeshing run of aprons. The proper drying of the material is important because the interlocking capacity of the material depends on the latter being thoroughly dry and set in its form, as a slight dampness of the material opens it and spoils its interlockable feature. Furthermore by reason of the holding of the material and drying during practically the entire run of the aprons the aprons may be run faster and consequently the output of the machine increased. After passing over said plate 28' it is removed onto the delivery table 56 by the stripper blades 52 at the time when the upper front roller 39 cooperates with the bars to spread them apart.

The lower front roller 39 can be provided with raised portions cut out to form sprockets which, similar to the sprockets 44, may engage the rods 21 to drive the apron instead of using the sprockets 44 and it is also to be noted that the corrugating bars need not be long bars but each of said bars could be made up of a plurality of short bars or links held together by the long hinge rods 21.

The invention thus exemplifies a method and a machine for producing corrugated material whereby the sheet material passing between the corrugation-forming aprons will be corrugated by said aprons.

The invention is not to be restricted to the details of construction herein set forth but may be varied so as to be within the scope of the appended claims, it being my intention to claim the same as broadly as will be permitted by the state of the prior art.

What I claim as my invention is:

40 1. A corrugation-forming apron comprising transversely extending corrugating bars, transversely extending rods pivotally connected to said bars, and chain links extending transversely of said bars and pivotally connecting said rods together to form a flexible corrugation forming endless apron.

50 2. A corrugating apron comprising corrugating bars having grooves on both sides, the grooves on adjacent bars forming apertures, means pivotally disposed within said apertures for allowing movement of the bars with respect to each other, and means for connecting said pivotally disposed means together.

55 3. A corrugating apron comprising corrugating bars, means for flexibly connecting said bars together in abutting relation with each other so that pressure applied to any one bar will be resisted by the adjoining bars.

60 4. A corrugating apron comprising bars having semi-circular grooves therein, the grooves of adjoining bars forming apertures, rods disposed within said grooves to permit

said bars to partially rotate thereon but to 65 resist any pressure tending to bend any of said bars, and means for joining said rods together whereby said bars will be joined together in series.

5. A corrugating apron comprising bars 70 having semi-circular grooves therein, the grooves of adjoining bars forming apertures between said bars, rods pivotally disposed within said apertures, said bars having a plurality of slots therein, and links disposed 75 within said slots and connected to said rods to form a flexible endless corrugating apron.

6. A corrugating apron comprising corrugating bars having semi-circular grooves 80 therein on each side, the grooves of adjoining bars forming apertures therein between said bars, round rods disposed in said grooves forming hinge centers for said bars, said bars having tapered sides below said hinge center to permit their movement toward or away from each other, and means for flexibly connecting said rods together.

7. A corrugating apron comprising abutting corrugating members, means for operatively connecting a series of said members 90 together to form an endless apron and means for holding said members rigid when led over a round support of predetermined diameter.

8. A corrugating apron comprising a plurality of abutting bars having corrugation-forming edges and bearing surfaces at the opposite ends, hinge connections for said corrugating bars whereby said edges of adjoining bars will spread apart when said bearing surfaces of said bars are led over a round support of predetermined diameter.

9. A corrugating apron comprising bars having corrugation-forming heads, hinge connections for said bars intermediate the top and bottom thereof and below the longitudinal axis through the center of gravity of said bars whereby said bars will have a slight swinging motion above said hinge connections.

10. A corrugating machine including in combination oppositely disposed interlockable flexible corrugation-forming aprons and supporting means for said aprons including flat supports and rollers of predetermined diameter, said aprons consisting of a plurality of corrugating bars having bearing surfaces running directly upon said supporting means, means for hingedly connecting the bars of each apron together so that they will stand out rigidly upon the rollers when passing thereover and so that the bars on opposite aprons will fold into each other when passing over said rollers and will be interlocked with each other while passing over said flat supports.

11. A corrugating apron consisting of a plurality of corrugating bars having corru-

gation-forming edges, each of said bars having grooves on their sides, said sides being straight and parallel between said grooves and the corrugation-forming edges and

5 slightly tapering from said grooves to the bottom edge of the bar, and means for connecting said bars together in series.

12. In a corrugating machine, the combination of a supporting frame and a plurality of rollers, and corrugation-forming means consisting of a pair of oppositely disposed intermeshing interlockable flexible aprons running over said rollers, each of said aprons consisting of a series of transversely extending corrugating bars hingedly connected together for limited movement about their hinge connection, each of said bars having a transversely extending corrugation-forming head portion and a transversely extending neck portion of less thickness than the head whereby the heads of the bars on one apron will fit into or be disengaged from the necks on the other apron when the bars of said aprons are 25 spread apart in passing over said rollers.

13. In a corrugating machine, the combination with a drive shaft and a plurality of gears and rollers mounted thereon, of a corrugating apron consisting of a series of corrugating bars, the tops of said bars having head and neck portions, the bottoms of said bars having surfaces bearing on said rollers and slots for receiving said gears, and a plurality of rods hingedly connected to said 35 bars and adapted to be engaged by the teeth of said gears to drive the apron.

14. In a corrugating machine, the combination with a drive shaft and a plurality of gears and rollers mounted thereon, of a corrugating apron consisting of a series of corrugating bars, the bottoms of said bars having portions shaped to form gear teeth to mesh with said gears, and having bearing portions for contacting with said rollers 45 and means for hingedly connecting said bars together.

15. In a corrugating machine, the combination with a shaft and a plurality of rollers mounted thereon, of a corrugating apron 50 consisting of a series of corrugating bars having bearing engagement with said rollers, means for hingedly connecting said bars together so that said bars will extend radially from said rollers when led thereover 55 and so that they will be relatively rigidly connected thereto.

16. In a corrugating machine, the combination of a plurality of corrugation-forming means joined together into a flexible 60 apron, supporting means including a roller over which said apron passes and provided with grooved portions, a bridge secured to the machine and having walls provided with bearing portions for receiving the grooved

portions of said roller to firmly support the 65 same whereby said corrugating means will be firmly supported in their entire length on said roller.

17. In a corrugating machine, the combination, with supporting means and driving 70 means, of a pair of oppositely disposed interlockable corrugation-forming endless aprons comprising a plurality of abutting bars having vent slots therein carried by said supporting means to receive and press 75 moistened material therebetween, and burners disposed below said aprons for drying the material while it is disposed thereon.

18. In a corrugating machine, the combination with supporting means and driving 80 means, of a pair of oppositely disposed interlockable corrugation-forming endless aprons carried by said supporting means to receive and press moistened material therebetween, means for drying said material 85 while disposed upon the aprons, and means for stripping said material from the aprons.

19. A corrugating machine comprising a pair of oppositely disposed intermeshing interlockable corrugation-forming flexible 90 aprons, means for supporting said aprons, means for permitting the spreading of the parts forming the aprons to introduce sheet material therebetween and remove the corrugated material therefrom, means for 95 feeding the material to the aprons, means for driving the aprons, and means for removing material from the aprons.

20. A corrugating machine comprising a pair of oppositely disposed flexible aprons, 100 each apron consisting of a series of interlockable corrugation-forming bars, the bars of said aprons intermeshing with each other to press and feed the material disposed therebetween, means for supporting said 105 aprons, means for hingedly connecting the bars of each of said aprons together to permit their spreading apart to introduce the sheet material between the aprons and remove the interlockable corrugated material 110 therefrom, means for feeding material between the aprons, means for driving the aprons, and means for removing the corrugated material from the aprons.

21. In a corrugating machine, the combination of a pair of oppositely disposed flexible endless aprons, each apron consisting of a plurality of interlockable corrugation-forming members hingedly connected together, the members of said aprons intermeshing with each other to press and feed the material disposed therebetween, supporting means for the apron comprising a frame and a plurality of rollers mounted on the frame, means on said members co-operating with said rollers to permit the spreading apart of said members to introduce the sheet material between the aprons 125

- and remove the interlockable corrugated material therefrom, means for feeding the sheet material between the aprons, means for driving the aprons, and means for retaining 65
5 moving the interlockable corrugated material from the aprons.
22. In a corrugating machine, the combination of a pair of oppositely disposed intermeshing flexible endless aprons, supporting means for said aprons, each apron consisting of a plurality of interlockable corrugation-forming parts hingedly connected together so that the parts will spread apart to receive and permit the removal of the 70
10 material between them and will close to press and feed the material between them, means for feeding the sheet material between the aprons, means for driving the aprons, and means for removing the interlockable corrugated material from the aprons. 75
15
23. In a corrugating machine, the combination of upper and lower interlockable corrugation-forming flexible aprons intermeshing with each other for a portion of their length, means for supporting said aprons, means for feeding material to the intermeshing portion of said aprons, means for stripping the material from the lower 80
20 apron, means for stripping the material from the upper apron, and means for driving one of said aprons, said driven apron serving to drive the other apron. 85
25
24. A corrugating apron comprising a plurality of rods, linkage for joining said rods together to form an endless apron, and a plurality of corrugating bars, each of said bars having an interlockable pivotal connection between adjacent rods. 90
30
25. A corrugating apron comprising a plurality of rods, flexible connections for joining said rods together to form an endless apron and a plurality of abutting corrugating bars, each of said bars disposed between adjacent rods and having a pivotal connection therewith to permit the spreading of 95
35 said bars with respect to each other. 100
40
26. A corrugating apron comprising a plurality of abutting bars having corrugating forming edges and tapered sides below said edges adapted to contact with each other to permit the spreading apart of said bars with respect to each other, and means for pivotally connecting said bars together 105
45 to form an endless flexible apron. 110
50
27. A corrugating machine comprising in combination a pair of oppositely disposed flexible aprons, each apron consisting of a series of transversely extending corrugation bars pivotally secured together, the bars of said aprons intermeshing with each other to press and feed the material disposed therebetween and to form transversely extending parallelly disposed interlockable corruga- 115
55 tions therein, means for supporting the aprons, means for driving the aprons, and means for removing the material from the aprons. 120
60
28. A corrugating machine comprising a pair of oppositely disposed flexible aprons, each apron consisting of a series of interlockable corrugation forming bars, the bars of said aprons intermeshing with each other to press and feed the material disposed therebetween, means for supporting each of said aprons comprising main rollers at opposite ends of the aprons and a pair of spreading rollers intermediate the main rollers and spaced away from the main rollers to spread the aprons, means for feeding the material to the aprons, means for driving the aprons and means for removing the material from the aprons. 125
65
29. A corrugating machine comprising a pair of oppositely disposed interlockable corrugation forming endless aprons, a frame inclosing the aprons, means for supporting the aprons within the frame, a partition dividing the frame into upper and lower compartments, means for heating each of said compartments, means for driving the aprons, and means for removing the material from said aprons. 130
70
30. In a corrugating machine, the combination of a pair of oppositely disposed flexible aprons, each apron consisting of a series of interlockable corrugation forming bars, the bars of said aprons intermeshing with each other to press and feed the material disposed therebetween, means for connecting the bars forming the aprons together to permit their spreading apart to introduce the sheet material between the aprons and remove the interlockable corrugated material therefrom, the bars of the upper apron being more loosely connected together than those of the lower apron to permit the introduction and removal of material between said aprons, means for feeding material between the aprons, means for driving the aprons, and means for removing the corrugated material from the aprons. 135
75
31. A corrugating apron comprising a plurality of abutting bars having corrugation-forming heads, hinged connections between said bars constructed and arranged so that said bars will have a slight swinging motion above and below their hinged connections. 140
80
32. In a corrugating machine, the combination of a plurality of corrugation-forming means joined together into a flexible apron, supporting means for said apron including a shaft and a roller carried thereby, a bridge secured to the machine and having walls provided with bearing portions for said shaft to firmly support the same at various points along its length. 145
85

33. A corrugating machine comprising a pair of oppositely disposed interlockable corrugation-forming endless aprons, a frame, means for supporting the upper and lower runs of each of the aprons in the frame, means for drying the material while held between aprons, means for removing

the material from one of the aprons, means for drying the material left on the other apron, and means for removing the material from this last named apron. 10

In testimony whereof, I affix my signature.

EMIL R. LOCHMAN.
